UNITED STATES PATENT OFFICE.

ALFRED CASSIRER, OF CHARLOTTENBURG, GERMANY.

DRYING-CHAMBER FOR ELECTRIC CABLES.

1,025,121.

Specification of Letters Patent.

Patented May 7, 1912.

Application filed November 30, 1908. Serial No. 465,329.

To all whom it may concern:

Be it known that I, ALFRED CASSIRER, mechanical engineer, a citizen of the German Empire, residing at 83 Berlinerstrasse, 5 Charlottenburg, in the Kingdom of Prussia, German Empire, have invented new and useful Improvements in Drying-Chambers for Electric Cables, of which the following is a specification.

10 This invention has for its object to provide an improved drying chamber for electric cables into which a number of cables may be introduced on their original drums with their axes horizontal for drying side 15 by side without having to transfer the cables on to special drying frames or stands and without having to swing or turn the drums out of the horizontal.

The improved drying chamber is further 20 designed to occupy a minimum floor space, while comprising very large heating surfaces distributed in a highly effective manner whereby almost the whole of the internal space of the chamber is rendered 25 available for drying purposes, so that there is the least possible amount of dead space.

Main objects of this invention are also to enable any one or more of the several cables to be placed into and removed from their 30 respective compartments of the drying chamber in any desired order without interfering with the other cables in the other compartments of the drying chamber, and also to insure that the cables in all the compartments 35 shall dry uniformly.

For the purpose of drying electric cables according to the methods heretofore in use, the cables have in most cases been unwound from their original drums (the drums upon 40 which the cables are coiled in the course of manufacture) and re-wound on to special drying stands.

The drying chambers used heretofore have been either of box-shape divided into 45 a number of superposed horizontal compartments into which the drying stands had to be pushed in on trucks or on pivoted or swinging frames, or the drying chambers have been made in the form of vertical or 50 horizontal cylinders.

In the case of vertical cylindrical drying chambers, the drying stands have been lowered in from the top.

In the case of a horizontal cylindrical dry- 55 ing chamber, one or both ends of the cylinder have been made to open out along the

axis of the cylinder and provided with an inwardly extending platform or platforms upon which the cable drums have been placed and so pushed into the drying chamber. Such drying chambers with their horizontal sliding out trucks and the rails for the trucks, or with their horizontally swinging frames, constitute bulky expensive and rather complicated structures.

The trucks or frames for charging the drying stands into the drying chamber, require outside the drying chamber almost as much floor space as the drying chamber itself, while they occupy inside the drying chamber a relatively large space whereby the space available for drying purposes is diminished.

A further disadvantage is that the transferring of the cables from their original drums to the drying stands occasions much trouble and loss of time.

Although in such drying chambers the cables can be introduced and removed in any desired order yet the cables in the various compartments do not dry uniformly because during the drying operation, the moist vapors that rise from the lowermost cables, must pass up along or through the upper cables, so that the order of removal 85 of the cables is not immaterial.

Even if the original drums were placed in such a drying chamber, the drawbacks attendant on the use of trucks and frames would still remain. Moreover the cable drums after being rolled up to the drying chamber, would still have to be set up on end for insertion into the drying chamber.

Cylindrical drying chambers as constructed hitherto, have the disadvantage that the heating surfaces are comparatively small, and that the drying heat can only be caused to radiate from the peripheral surface of the cylinder, with perhaps the addition of one end.

In the case of vertical cylindrical drying chambers the cables have mostly been re-wound with great trouble on special drying stands. While when it has been desired to avoid this rewinding and to dry the cables on their original drums it has been necessary to turn these drums on end when they have been rolled up to the drying chamber before they could be charged into the latter. In this case also there is the disadvantage that the upper cables dry with more difficulty than the lower cables.

In horizontal cylindrical drying chambers, it has been necessary to lift the drums on to the internal platform or platforms attached to the removable end or ends of the 5 chambers, and then to push the drums into the chamber. These platforms however require outside the drying chamber almost as much floor space as the chamber itself, and inside the chamber they take up a considerable 10 space which reduces the space available for drying.

When it has been desired to dry a number of cables at the same time in one of those vertical or cylindrical drying chambers, 15 it has been necessary to remove the drums or drying stands in the reverse order to that in which they were charged into the chamber. Consequently when it has been desired for instance to work upon the cable 20 that was charged in first and to allow the other cables to remain some time longer in the chamber and it has been necessary first to take out all the said other cables and then after removing the desired cable to charge 25 the said other cables back into the drying chamber.

Now all the aforesaid disadvantages are obviated according to the present invention which consists substantially in dividing the 30 drying chamber by means of vertical parallel plane heating partitions into separate compartments into which the cables can be introduced for drying on their original drums with their axes horizontal, by being 35 lowered in from the top.

One form of the improved apparatus is illustrated by way of example in the accompanying drawings in which—

Figure 1 is a cross section on the line 40 A—A of Fig. 2; and Fig. 2 is a longitudinal section on the line B—B of Fig. 1.

In the example shown, the drying chamber consists of a vessel, *a*, (hereinafter called the chamber) of rectangular shape in plan. 45 This chamber, *a*, is open at the top, and closed at its four sides and at the bottom. The opening at the top is adapted to be closed air-tight by means of a lid, *b*. The bottom of the chamber may be of semi-cylindrical form.

The interior of the chamber is divided by means of a number of vertical heating partitions into a corresponding number of compartments.

55 In the example shown, five such heating partitions are provided which divide the chamber into four separate compartments. Each heating partition is composed of a serpentine tube, *c*, winding to and fro in the vertical plane of the partition. Steam is caused to flow through each tube, *c*, for the purpose of heating the chamber. The steam is admitted at *d* at the highest point of each serpentine tube, and passes out at the lowest 65 point, *e* of the tube.

The lid, *b*, is adapted to be made tight by means of packing, and it can be raised to a sufficient extent to leave the opening of the chamber wholly unobstructed.

f is a pipe by means of which the air can 70 be exhausted from the closed chamber so as to allow the cables to be dried in a vacuum.

The chamber, *a*, is preferably sunk to a suitable extent below the floor of the work-shop.

75 The cables to be dried are rolled along to the drying chamber on their original drums and then lowered by a crane into the several compartments between the heating partitions. In this manner only the floor space 80 occupied by the actual chamber is required.

No swinging or turning of the cable drums is necessary.

The large heating surfaces are situated close up to the drums so that a rapid and 85 uniform heating of the cables is insured.

The dead or unoccupied space in the chamber is reduced to a minimum.

Transporting devices such as trucks carriages and the like, are not required in the 90 chamber.

The several cables can be placed into and removed from the chamber in any desired order.

The cables placed in the several compartments are dried in a uniform manner.

Owing to there being no longer any necessity for unwinding the cables from their original drums and re-winding them on to special drying stands, or for swinging or 100 turning the drums, the operation of drying the cables is much facilitated by the improved drying chamber.

Having thus described my invention, I claim as new:

105

1. In a drying chamber for electric cables, the combination with a vessel, of heating means arranged to provide vertical partition walls, dividing said vessel into separate compartments, adapted to receive the cable 110 drums with their axes horizontal and an opening provided at the top of said vessel allowing cable drums to be placed with their axes horizontal into said compartments.

2. In a drying chamber for electric cables, 115 the combination with a vessel having a semi-cylindrical bottom, of heating means arranged to provide vertical partition walls, dividing said vessel into separate compartments, adapted to receive the cable drums 120 with their axes horizontal, and an opening in said vessel allowing cable drums to be placed with their axes horizontal into said compartments.

3. In a drying chamber for electric cables, 125 the combination with a vessel, of serpentine steam pipes arranged to form vertical partition walls dividing the vessel into separate compartments adapted to receive the cable drums with their axes horizontal, and an 130

opening provided at the top of said vessel allowing cable drums to be placed with their axes horizontal into said compartments.

4. In a drying chamber for electric cables, 5 the combination with a vessel, of heating means arranged to provide vertical partition walls, dividing said vessel into separate compartments, adapted to receive the cable drums with their axes horizontal, an opening provided at the top of said vessel allowing cable drums to be placed with their axes horizontal into said compartments, and means to produce a vacuum within said vessel.

15 5. In a drying chamber for electric cables, the combination with a vessel having an opening in its top, of serpentine pipes arranged to form hollow vertical partitions dividing the vessel into separate compartments adapted to receive cable drums with their axes horizontal, means for circulating steam through said partition walls from the top to the bottom thereof, and means for hermetically sealing the open top of the vessel.

25 6. In a drying chamber for electric cables, the combination with a vessel having an

opening in its top, of a steam pipe entering it at the top and emerging therefrom near the bottom and arranged to form a vertical 30 partition dividing the vessel into compartments of a form to receive cable drums with their axes horizontal, means for circulating steam through said partition from the top to the bottom, means for hermetically sealing the opening in the top of the vessel, and a pipe leading from the interior of the vessel adapted to connect with means for producing a vacuum in the vessel.

7. A drying chamber for electric cables 40 comprising a vessel having an opening in its top, of a parallel spaced apart series of steam pipes entering the side near the top, arranged inside the vessel into serpentine transverse coils forming partitions, and 45 leading out at the bottom of the vessel, and a longitudinal exhaust pipe below the vessel receiving the lower ends of the steam pipes.

In witness whereof I have hereunto set my hand in presence of two witnesses.

ALFRED CASSIRER.
